COMBINED PICTURE AND ILLUMINABLE PICTURE FRAME

Laurence C. Helms, Grand Rapids, Mich., assignor to
Helms Products, Inc., Grand Rapids, Mich., a corpora-
tion of Michigan

Application June 10, 1954, Serial No. 30,914

Term of patent 14 years

(Cl. D29—20)

FIG. 3.

FIG. 2.

FIG. 4.

To all whom it may concern:

Be it known that I, Laurence C. Helms, a citizen of the United States, residing in Grand Rapids, county of Kent, State of Michigan, have invented a new, original, and ornamental Design for a Combined Picture and Illuminable Picture Frame, of which the following is a specification, reference being had to the accompanying drawings, forming a part thereof.

Fig. 1 is a perspective view of a combined picture and illuminable picture frame showing my new design.

Fig. 2 is a front elevational view thereof.

Fig. 3 is a plan view thereof; and

Fig. 4 is an end view thereof.

I claim:

The ornamental design for a combined picture and illuminable picture frame, substantially as shown.
